UNITED STATES PATENT OFFICE.

HENRY BRAMMER, OF ST. LOUIS, MISSOURI.

GEARING FOR WASHING-MACHINES.

No. 882,619.

Specification of Letters Patent. Patented March 24, 1908.

Application filed June 27, 1907. Serial No. 381,095.

To all whom it may concern:

Be it known that I, HENRY BRAMMER, a citizen of the United States, and a resident of St. Louis, in the State of Missouri, have 5 invented certain new and useful Improvements in Gearing for Washing-Machines, of which the following is a clear, full, and exact description.

My invention relates to mechanical movements for converting a continuously revolving motion into a rotary reciprocal motion, and it is particularly adapted for use in connection with "rotary washing machines".

The object of my invention is to provide 15 mechanism which will cause a rotary reciprocal shaft to run smoothly but at an uneven speed throughout its cycle of movement, and will not pound at the moment of reversal nor reverse too quickly. This I accomplish by 20 the means hereinafter fully described, and as particularly pointed out in the claims.

In the drawings:—Figure 1 is a side elevation of my invention. Fig. 2 is a plan view 25 of a portion of the same showing the supporting frame broken away. Fig. 3 is a view showing one side of the mangle-gear. Fig. 4 is a similar view of the opposite side thereof.

In the drawings A represents a suitable supporting-frame for the operative parts of 30 my invention. This supporting-frame comprises a suitable base-plate, which is secured to the lid or cover of the tub of a washing machine (not shown) and has one end terminating in a suitable bearing for the outer 35 end of a continuously revolving drive-shaft B and the other end provided with a somewhat circular shaped arch that has a horizontal bearing for the inner end of the drive-shaft, and vertical bearings for the rotary 40 reciprocal driven shaft C, and parts coöperating therewith whose axes aline with that of the driven shaft, as will hereinafter be more fully described.

The upper end of shaft C extends above its 45 bearings in the base-plate of the supporting-frame and is provided with a beveled pinion b, and it projects above the upper face of said pinion a short distance and its upper end serves as a pilot or pivot for a rotary reciprocal bearing block c, which latter has a downwardly extending boss or block c' with an opening therein for the reception of the upper end of said shaft C, and has an upwardly extending boss whose bore is adapted to receive 50 the downwardly extending end of a short spindle secured, in alinement with shaft C in

the overhead portion of the arch of the supporting-frame, substantially as shown.

The bearing in block c is horizontal and when in the position shown in Fig. 1 of the drawings alines with the axis of the drive-shaft. Journaled in this bearing is a rotary reciprocal shaft D, whose end, nearest the drive-shaft, has a wheel E secured thereto, which has a bevel gear d on the side nearest the pivot of said block c which meshes with pinion b and on its opposite face is provided with a series of circularly arranged pins e projecting therefrom. This series of pins extends about three-fifths of a circle, more or less, and the face of the gear from which they project is provided with an endless tracker groove or runway f, which surrounds the base of said pins, and at every point throughout its length is an equal distance removed from the circular line intersecting their centers. Now the adjacent end of the drive-shaft extends sufficiently beyond its adjacent bearings to enter runway f, and it has near its extremity a spur-wheel F which is adapted to mesh with pins e, and which is held in engagement therewith by reason of the extremity of the drive-shaft traveling in said runway.

The operation of my invention is substantially as follows, to-wit: When the drive-shaft is revolved continuously in one direction, the spur-wheel F thereof engages the pins e of the mangle-wheel E and turns the shaft D first in one direction and then in another. In order to do this, however, in view of the fact that said spur-wheel engages the sides of the pin, farthest from the center of rotation of the mangle-wheel and then the side of said pins nearest the said center of rotation, the shaft B vibrates laterally and moves said mangle-wheel so that its center of rotation approaches nearer to and then farther from the spur-wheel, said mangle-wheel traveling faster while the spur-wheel 100 engages the sides of the pins nearest the center of rotation of the mangle-wheel and slower when the spur-wheel engages the end pin of the series, and the sides of the pins farthest from the center of said wheel. Thus 105 a very uneven speed is imparted to the mangle-wheel and through the beveled gear d to the beveled pinion b and the rotary reciprocal shaft D to which it is secured.

What I claim as new is:—

1. A mechanical movement comprising a continuously revoluble drive-shaft, a rotary

reciprocal shaft arranged at an angle there-
to, and rotary reciprocal means deriving its
motion from said drive-shaft having a trans-
versely vibratory axis and operatively con-
nected to and imparting its motion to said
rotary reciprocal shaft.

2. A mechanical movement comprising a
continuously revoluble drive-shaft, a rotary
reciprocal shaft arranged at an angle there-
10 to, and rotary reciprocal means deriving its
motion from said drive-shaft on one side and
engaging the rotary reciprocal shaft on the
opposite and having a transversely vibratory
axis and operatively connected to and
15 imparting its motion to said rotary reciprocal
shaft.

3. A mechanical movement comprising a
continuously revoluble drive-shaft, a rotary
reciprocal shaft arranged at an angle there-
20 to, a rotary reciprocal mangle-wheel deriv-
ing its motion from said drive-shaft having a
transversely vibratory axis and having a pin-
ion integral with its side opposite said drive-
shaft which is operatively connected to and
25 imparts its motion to said rotary reciprocal
shaft.

4. A mechanical movement comprising a
continuously revoluble drive-shaft, a rotary
reciprocal shaft arranged at an angle there-
30 to, a rotary reciprocal mangle-wheel deriving
its motion from said drive-shaft having a
transversely vibratory axis and having a pin-
ion integral with its side opposite said drive-
shaft which is operatively connected to and
35 imparts its motion to said rotary reciprocal
shaft.

5. A mechanical movement comprising a
continuously revoluble drive-shaft, a rotary

reciprocal shaft arranged at an angle there-
to, a rotary reciprocal mangle-wheel-shaft to 40
which said rotary reciprocal shaft is secured,
pivoted bearings for said mangle-shaft in the
same plane as the bearings of said drive-
shaft, the axis of the pivot of which alines
with the axis of said rotary reciprocal shaft, 45
and means integral with said mangle-wheel
that is operatively connected to and imparts
its motion to said rotary reciprocal shaft.

6. A mechanical movement comprising a
continuously revoluble drive-shaft, a rotary 50
reciprocal shaft arranged at an angle there-
to, a rotary reciprocal transversely vibratory
mangle-wheel deriving its motion from said
drive-shaft, having a concentric segmental
series of pins projecting therefrom and a 55
tracker groove surrounding and at all points
equi-distant from the same.

7. A mechanical movement comprising a
continuously revoluble drive-shaft, a rotary
reciprocal shaft arranged at an angle there- 60
to, a rotary reciprocal transversely vibratory
mangle-wheel deriving its motion from said
drive-shaft having a vibratory movement in
a plane transaxial to said drive-shaft; having
a concentric segmental series of pins project- 65
ing therefrom, and a tracker groove surround-
ing and at all points equi-distant from the
same.

In testimony whereof I have hereunto set
my hand and seal this 12th day of June, 70
A. D. 1907.

HENRY BRAMMER. [L. S.]
